Primary Examiner — Sheryl Lane(74) *Attorney, Agent, or Firm* — Benesch, Friedlander, Coplan & Aronoff, LLP; Thomas Y. Kendrick; Christopher H. Bond(57) **CLAIM**

The ornamental design for a material manipulation tool, as shown and described.

DESCRIPTION

FIG. 1 is a front/top perspective view of a material manipulation tool;

FIG. 2 is a front/bottom perspective view thereof;

FIG. 3 is a top plan view thereof, with the handle separated into multiple components and disconnected from the blade;

FIG. 4 is a right side elevation view thereof;

FIG. 5 is a left side elevation view thereof;

FIG. 6 is top perspective view thereof;

FIG. 7 is a bottom perspective view thereof;

FIG. 8 is a top perspective view thereof, with the handle separated into multiple components and disconnected from the blade; and,

FIG. 9 is a rear elevation view thereof.
